UNITED STATES PATENT OFFICE.

CARL HUMPERDINCK, OF WETZLAR-LAHN, GERMANY.

PRODUCTION OF HOLLOW BODIES BY CENTRIFUGAL CASTING.

Application filed November 10, 1926, Serial No. 147,498, and in Germany November 10, 1925.

In order to convey metal in molten state from casting ladles into the interior of rotating centrifugal casting moulds, different forms of casting channels or casting tubes 5 have been used which are either rotatable or stationary. The disadvantages of casting channels reside in the loss of heat incurred by the molten metal in its long path through them, the metal becomes oxidized and in- 10 crustations form on the walls of the casting channels and casting tubes and on the surfaces of the molten metal.

Casting channels or casting tubes in which the cross sectional area of flow is about one-half or two-thirds filled, in consequence of the intense heating on one side become distorted, so that an increased casting operation is hardly possible. With such rapidly rotating casting tubes, on account of the uni- 15 lateral application of the weight by bent tubes or by weight of the fluid metal, bending and consequent shaking of the casting tubes occurs.

The above-mentioned disadvantages of 20 known casting tubes are avoided in accordance with the present invention by imparting to them during the passage of the molten metal therethrough a transverse swinging movement of continuously changing direc- 25 tion.

Devices suitable for performance of this method are illustrated by way of example in the accompanying drawing in which:

Fig. 1 is a longitudinal section through 30 the casting device,

Fig. 2 is an end view of one form of the metal receiving head, while

Fig. 3 is a corresponding view of another form of the receiving head.

Molten metal is poured from the casting 35 ladle A into the hopper B. From this stationary hopper the metal flows into the receiving head C connected with the casting tube D and thence through the casting tube 40 into the interior of the centrifugal casting mould E. The casting tube D is rotatably mounted in a standard F. When the molten metal is delivered to the centrifugal casting mould E the machine is caused to travel a

distance corresponding to the length of the pipe to be formed. While the molten metal 45 is passing from the hopper B into the receiving head C and through the casting tube

D, the casting tube with its receiving head is given an oscillating motion by means of 55 a lever H secured thereto, Fig. 2.

As a result the metal within the casting tube moves around the walls thereof and washes off any projection which would induce the formation of incrustation. Moreover, non-uniform heat transmission 60 through the covering of the casting tubes is avoided—a matter of great importance in view of the distortion of the casting tube.

In lieu of fitting the casting tube with a 65 hand lever it may be provided with a toothed segment meshing with a pinion H² adapted to be rotated alternately in opposite directions, providing for effecting mechanically the swinging movement of the casting tube. 70

I claim:

1. The method of producing hollow bodies, such as tubes, by centrifugal casting, which includes imparting to the casting tube during the passage of the molten metal 75 lengthwise thereof a transverse vibratory movement of alternately varying direction.

2. In apparatus for the production of hollow bodies by centrifugal rotatable casting, including a casting mould and an open 80 ended casting tube, means located externally of the casting mould for imparting to the casting tube an oscillatory movement about its longitudinal axis.

3. In a rotary casting machine, the combination of a rotary mould, a metal delivery tube disposed therein and having an open end for the delivery of the molten metal, said mould and said tube being relatively movable longitudinally during the delivery 90 of the metal to distribute the metal lengthwise of the mould, and means for imparting to said tube an oscillating movement about its longitudinal axis during said longitudinal movement.

4. A rotary casting machine, including a rotary mould mounted for longitudinal movement, a casting tube projecting into the mould and having an open end, and means for oscillating the tube about its longitudinal 95 axis.

5. A rotary casting machine having a stationary hopper, a metal delivery tube disposed substantially horizontal and having an open end, means for oscillating said tube 100 about its longitudinal axis, and means con-

nected to said tube for delivering metal thereto from said hopper during said oscillatory movement.

6. In a rotary casting machine, a metal delivery tube having an open end, and means for oscillating the tube back and forth during the flow of metal therethrough, said tube having means permitting the delivery of metal thereto during said oscillating movement.

7. The method of forming hollow cast bodies which includes rapidly rotating the mould, delivering metal thereto from an

open ended pipe, effecting a relative longitudinal movement of the mould and tube, and simultaneously effecting an oscillating movement of said tube.

8. The method of producing hollow bodies which includes rotating the mould, delivering metal thereto through a tube, and simultaneously oscillating said tube and effecting a relative longitudinal movement of the tube and mould.

In testimony whereof I have signed my name to this specification.

CARL HUMPERDINCK.
